BARREL LIFTING MEANS

Lloyd L. Babcock, Compton, and James O. Bishop,
Torrance, Calif.

Application June 1, 1942, Serial No. 445,314

5 Claims. (Cl. 294—110)

This invention relates to a barrel lifting means whereby metal barrels, drums, or the like may be gripped and lifted for the purpose of moving or transporting the barrels or drums to another position.

The prime object of our invention is to provide a semi-automatic barrel lifting means, which grips metal barrels, drums or the like by the chime so that the barrel, or the like, can be easily lifted and then transported and set in another position with a maximum efficiency of time and space. Barrels, drums, or the like are generally stored on end, the reason being that this saves space and is also more safe for the worker, the equipment, and the supplies in the barrels. The handling of these containers usually involves trucking on hand or power trucks, or lifting them by hand or with power hoists. Occasionally cylindrical containers are also tilted onto their cylindrical sides and then rolled and then re-tilted onto their ends or heads. All of these methods of handling require costly and hazardous operations, which are entirely eliminated by the use of our invention. In using a hand truck, equipment of considerable value must be employed. This method also requires that the barrel, or drum, be partially tilted by hand, after first being separated by a few inches from the wall or other containers. Frequently one person cannot perform this operation alone. There is considerable hazard to the workman, due the possibility of slipping, or otherwise injuring parts of the body. Unloading the container from the truck requires other strains upon the workman, and if the space is to be conserved, the containers must be slid bodily against adjacent objects. Heretofore the handling of barrels, drums, or the like by means of hoists required the use of a sling, or tongs, or clamps, which engaged the containers, usually by pressing against the wall. The application of the clamping means required some hand tilting or sliding as well as time-consuming manipulation of the hand apparatus. The engagement of the wall and the container frequently resulted in damage because of the high crushing stress. Furthermore there was a possibility of the container slipping out of the engaging means.

Another object of our invention is to provide a novel barrel lifting means, which grips the chime of the container and thus it is possible to single out and lift a single barrel or drum from surrounding barrels without moving or disturbing the other barrels or drums.

A feature of our invention is to provide a novel barrel lifting means which is adjustable

so as to fit barrels and the like of various sizes and also which will automatically engage or release the barrel or the like.

5 Other objects, advantages and features of invention may appear from the accompanying drawing, the subjoined detailed description and the appended claims.

In the drawing

10 Figure 1 is a side elevation of our barrel lifting means.

Figure 2 is a fragmentary side elevation of our barrel lifting means, with parts broken away to show interior construction.

15 Referring more particularly to the drawing, our barrel lifting means includes a frame 1, which is of inverted T shape and preferably formed of tubular parts. The frame 1 includes a horizontal member 2 and a vertical member 3. A sleeve 4 is slidably mounted on the member 3, and a cap 5 is threaded or otherwise fixedly attached to the upper end of the sleeve. A ring 6 is swivably mounted in the cap 5, for example, by means of a nut 7 which screws onto the shank of the ring, the nut being positioned within the cap 5. A pair of posts 8 and 9 are slidably mounted in the horizontal member 2 and project from each 20 end of this member, substantially as shown. A head 10 and 11 is formed or fixedly attached to the outer end of the posts 8 and 9, respectively. A dog 12 is formed or fixedly attached to the outer end of each of the heads 10 and 11 for the purpose of gripping the inner surface of the chime 13 on a barrel or the like 14. The posts 25 8 and 9 are slidable in the member 2 and thus the heads 10 and 11 can be moved in and out to engage barrels of different diameters.

A pair of lugs 14 and 15 are formed on or fixedly attached to the sleeve 4. A pair of links 40 16 and 17 are pivotally attached to the heads 10 and 11, respectively, by the pins 18 and 19, respectively. At their inner ends the links 16 and 17 are pivotally attached to the lugs 14 and 15, respectively, by the pins 20 and 21, respectively.

45 The connection of the links to the lugs is slideable, preferably by means of a slot 22 and 23 in the lugs 14 and 15, respectively, and through which the pins 20 and 21, respectively, extend. The lower faces of the links 16 and 17 are each tapered, as shown at 24 which act as a cam when the chime of the barrel is engaged, thus enabling the barrel lifter to automatically engage the barrel. The cable of a hoist or boom is attached to the ring 6 and swung into position over a 50 barrel by the workman's hands, then dropped

onto the barrel, thus causing the dogs 12 to engage the chime of the barrel. The complementary dogs 25 on the links 16 and 17 engage the outside of the chime, thus effectively gripping the barrel and enabling the operator to lift the barrel from its position and transport it to another place. The outside diameter of our barrel lifting means is such that barrels can always be selected from a number of them on a floor, since there is always enough space between the barrels to permit our device to engage any barrel.

Having described our invention, we claim:

1. A barrel lifting means comprising a frame, a pair of posts slidably mounted in said frame, chime engaging means on the outer end of each of the posts, lifting means mounted on the frame, said lifting means being movable relative to the frame, chime gripping means cooperating with said first-named chime engaging means, and means connecting said chime gripping means to said lifting means, whereby said chime gripping means is actuated as the lifting means is moved upwardly by the operator.

2. A barrel lifting means comprising an inverted T-shaped frame, including a horizontal member and a vertical member, a pair of posts slidably mounted in the horizontal member, a chime engaging dog on the outer end of each of said posts, a sleeve slidably mounted on said vertical member, coupling means on the sleeve, a link pivotally attached to each of said posts, each of said links being pivotally attached to said sleeve, and each of said links being adapted and arranged to engage the outside of the chime of a barrel.

3. A barrel lifting means comprising an inverted T-shaped frame, including a horizontal member and a vertical member, a pair of posts slidably mounted in the horizontal member, a chime engaging dog on the outer end of each of said posts, a sleeve slidably mounted on said ver-

tical member, coupling means on the sleeve, a link pivotally attached to each of said posts, each of said links being pivotally attached to said sleeve, and each of said links being adapted and arranged to engage the outside of the chime of a barrel, each of said links having a slidable, pivotal connection of said sleeve.

4. A barrel lifting means comprising a substantially T-shaped frame, including a tubular horizontal member and a vertical member, a sleeve slidably mounted on the vertical member, a link mounted on said sleeve, a pair of lugs on said sleeve, a pair of posts slidably mounted in said horizontal member, a head on the outer end of each of said posts, a dog on each of the heads, engageable with the inside of a barrel chime, a link pivotally attached to each of the heads, said links being pivotally attached to a lug with a lost-motion connection, and a dog on each of the links cooperating with said first-named dogs to grip the chime of a barrel.

5. A barrel lifting means comprising a substantially T-shaped frame, including a tubular horizontal member and a vertical member, a sleeve slidably mounted on the vertical member, a link mounted on said sleeve, a pair of lugs on said sleeve, a pair of posts slidably mounted in said horizontal member, a head on the outer end of each of said posts, a dog on each of the heads, engageable with the inside of a barrel chime, a link pivotally attached to each of the heads, said links being pivotally attached to a lug with a lost-motion connection, and a dog on each of the links cooperating with said first-named dogs to grip the chime of a barrel, and each of said links having a tapered surface at the outer ends thereof engageable with the barrel chime to operate said dogs and permit engagement of the barrel chime.
